UNITED STATES PATENT OFFICE

102,425

DESIGN FOR A FLY SWATTER

Milton Wallace Gatch, Baltimore, Md.

Application November 9, 1935, Serial No. 59,464

Term of patent 3½ years

To all whom it may concern:

Be it known that I, Milton W. Gatch, a citizen of the United States, residing at Baltimore, in the State of Maryland have invented a new, original, and ornamental Design for a Fly Swatter, of which the following is a specification, reference being had to the accompanying drawing, forming part thereof, in which:

Fig. 1 is a front elevational view of a fly swatter showing my new design; and

Fig. 2 is an end view of the handle portion looking in the direction of the arrows on line 2—2 of Fig. 1.

The dominant feature of my design resides in the handle portion shown in full lines.

I claim:

The ornamental design for a fly swatter, substantially as shown and described.

MILTON WALLACE GATCH.
